PRINTING TELEGRAPH APPARATUS

Albert H. Reiber, Evanston, Ill., assignor to Teletype Corporation, Chicago, Ill., a corporation of Delaware

Application November 27, 1935, Serial No. 51,751

13 Claims. (Cl. 197—84)

This invention pertains to printing telegraph apparatus and more particularly to such apparatus capable of tabulation recording.

It is the principal object of the invention to provide in a recording device a simple, efficient, and reliable tabulating device which is operable automatically at predetermined intervals for controlling tabulation recording.

A feature of the invention resides in the provision of cam means effective automatically at predetermined intervals to insert an extra character space without interrupting transmission or reception of character code signals.

The above and other objects of the present invention are accomplished by the provision in a printing telegraph apparatus of the type disclosed in U. S. Patent No. 1,904,164, of a tabulator bar which extends across the front of the machine and is pivotally carried by brackets mounted in the typing unit and capable of swinging toward and away from the type carriage. The tabulator bar carries a number of adjustable members which determine the positions at which the type carriage is automatically spaced a plurality of character spaces during the time interval corresponding to a single character code signal. The spacing mechanism of the printing apparatus comprises a multi-toothed ratchet adapted to cooperate with a pair of pawls which are actuated by the printing bail to function as an escapement mechanism so that, upon each revolution of the main shaft, the spacing worm gear associated with the spacing ratchet is permitted under normal operating conditions to escape one tooth at a time and hence to rotate through a corresponding angle.

According to the present invention, the use of a function lever to accomplish multiple spacing of the type carriage is obviated, and instead the tabulator bar acts directly upon a space pawl release lever through the instrumentality of a cam surface formed at the lower end of a depending arm integral with the tabulating bar. As the type carriage passes any one of the adjustable members, the tabulator bar is rotated so that the cam surface causes similar rotation to the pawl release lever to raise the rear end thereof. When the rear end of the pawl release lever is raised, it lifts, through suitable linkage, the upper space pawl out of engagement with the tooth of the spacing ratchet. While the upper space pawl is thus disengaged, the lower space pawl returns to its normal position free of the teeth on the escapement ratchet, thus permitting the spacing worm gear to make approximately

one complete revolution instead of only a fraction of a revolution during the time that the main shaft rotates through one revolution, and therefore the carriage will be spaced continuously a distance, per revolution of the main shaft, which is in excess of the normal spacing distance.

It is obvious that the spacing ratchet may be provided with any number of teeth, and hence the number of character spaces capable of being procured during a complete revolution of the spacing ratchet is governed by the number of teeth on the spacing ratchet. Of course, the width of each space is governed by the conformation of the teeth on the spacing worm and the gears cooperating therewith. Furthermore, by governing the duration of disengagement of the upper space pawl any intermediate number of spaces may be procured during a single rotation of the operation of main shaft. To bring the carriage to rest after tabulating or multiple spacing, it is necessary to permit the upper space pawl to drop again into engagement with a tooth on the spacing ratchet. This latter function is effected whenever the cam element assembled to the traveling type carriage passes out of coactive relation with the adjustable members carried by the tabulator bar. Normally, the tabulator bar is biased toward the type carriage and at predetermined positions of the carriage the cam element forces or cams the tabulator bar forward or away from the carriage, against spring tension, and in doing so causes the pawl release lever to be acted upon by the cam shoe or surface to disengage in turn the upper space pawl for a period of time determined by the contour of the cam face of the adjustable member, after which period the upper space pawl again falls into engagement with a tooth on the spacing ratchet to bring the carriage to rest. With the apparatus according to the present invention, a received message may be recorded in such a manner as to form automatically a record made up of a plurality of vertical columns of equal width.

A better understanding of the invention may be had from the following description, taken in conjunction with the accompanying drawings wherein,

Fig. 1 is a partial front elevation of the printing apparatus showing the application of the tabulating and lock-out mechanisms thereto;

Fig. 2 is a sectional plan view of the printing apparatus corresponding to Fig. 11 in Patent No. 1,904,164 with the addition of the multiple spacing mechanism according to the present invention;

Fig. 3 is a transverse cross-sectional view of the printer taken approximately through the vertical center line of Fig. 1, and

Fig. 4 is a detail rear elevation of the spacing mechanism of the printing apparatus covered by said patent.

In the accompanying drawings like reference characters indicate similar parts throughout. For a complete understanding of details not disclosed herein which form no part of the present invention, reference may be had to U. S. Patent No. 1,904,164, issued April 18, 1933, to S. Morton et al.

Briefly, having reference to Figs. 1, 2, and 3, a printing apparatus to which the tabulating mechanism of the present invention is applied comprises a typing unit which includes a primary selecting mechanism indicated generally as 11 (Fig. 2) which is of the sword-and-T type disclosed in U. S. Patent No. 1,745,633 to S. Morton et al. (fully disclosed in the first mentioned patent), and a secondary selector or selector vane assembly indicated generally as 12. The selector vane assembly 12 controls through a series of bell 15 cranks 13 (Fig. 1) a corresponding series of curved code bars 14 carried in a movable type carriage. As set forth in the first mentioned patent, this type carriage, indicated generally as 15, is movable longitudinally in respect to a stationary platen indicated generally as 16 (Fig. 3). The type carriage 15 also carries a ribbon feed mechanism indicated generally as 17.

Referring particularly to Fig. 2, a motor 18 supplies power through gear 19 to a main operating shaft 21 which carries the spacing mechanism indicated generally as 22, and the selector cam assembly indicated generally as 23. As is known in this type of device, power is communicated from the motor to the driven shaft through a grab clutch such as 25. Portion 24 of grab clutch 25 constantly rotates with the shaft 21, which has also frictionally connected thereto the spacing mechanism 22 and the selecting cam drum 23. Portion 24 is cooperatively engaged with the driven portion 26 when throw-out lever 27 is operated in timed relation with the reception of code signals.

The spacing mechanism 22, which will be described more in detail hereinafter, controls, through gear 28, shaft 29, gear 31, and rack 32 (Fig. 3), the movement of type carriage 15 to form character spaces, tending in this movement to wind up the carriage return spring mechanism indicated generally as 33. Upon receipt of the carriage return signal, function bar 34 is actuated selectively in the manner described in Patent 1,904,164 so as to permit spring 35 to rotate lever 36 suddenly against stop 37 to raise, through bell crank 38, portion 39 of grab clutch 41. Carriage return mechanism 33 is thereupon permitted, due to the energy stored up therein, to return the carriage 15 to its normal or beginning-of-line position.

Positioned in operative relation with and parallel to the main operating shaft 21 is an auxiliary shaft 42 on which are carried various mechanisms; for example, printing bail 43, function lever bail 40, and the escapement mechanism for the spacing mechanism 22. The printing bail 43, which is actuated by a printing spring (not shown) in proper timed relation in the operative cycle, functions to reciprocate a pull bar operating member 44 to cause the operation of a type bar, as clearly described in the aforementioned patent.

The selector vanes as set forth in Patent No. 1,904,164 control a series of function levers 45 which are pivoted on a common pivot rod 46 and are assembled in a slot in the function lever comb 47. The function levers 45 are provided with individual springs 48 tensioned between each lever and the printer frame, which tend to rotate the respective function levers 45 about pivot 46 but, as clearly set forth in Patent No. 1,904,164, are restrained by the function lever bail 49 acting through rod 50 on arm 60.

Before describing further the tabulating or multiple spacing mechanism, a detailed description of the spacing mechanism will be given. Having reference to Figs. 3 and 4 there is shown mounted on the main shaft 21 and located centrally of the apparatus a sleeve member 51 which comprises escapement ratchet 52 and spacing worm 53 which are operably connected thereto. Sleeve member 51 is operably connected to the hub of a disc 54 by means of inter-engaging tongue and groove members 55. Collar 56 is pinned to main shaft 21 and is rotatable therewith. Interposed between disc 54 and collar 56 is disc 57 of frictional material; for example, felt. By means of a helical compression spring 58, sleeve 51 is frictionally connected to shaft 21 through the friction clutch comprising members 54, 56, and 57. Sleeve 51 is thereby rotatable with main shaft 21 unless arrested by the escapement pawls of the spacing mechanism 22, as will presently appear.

Referring to Fig. 3 it will be noted that ratchet 52 is provided, for example, with three teeth or notches 61, 61a, and 61b, the escapement of which will allow the type carriage 15 to be moved forward one step or character space for each actuation of the printing bail 43. As indicated, the escapement mechanism comprises a pair of pawls or levers 62 and 63, pivotally mounted on bail 40 shaft 42, and lever 64 adjustably fixed to printing bail 43. Spring 65 normally tends to bias levers 62 and 63 toward each other, since it is common to both levers. Lever 62 is normally urged by spring 65 in a counterclockwise direction so that laterally disposed end 66 engages tooth 61 of ratchet 52, thus arresting the rotation of said ratchet. Lever 63 is normally held out of engagement with ratchet 52 against the tension of spring 65 by the action of lever 64 against laterally disposed end 67.

Lever 64 is pivotally connected to printing bail 43 at 68 and is provided at 69 with a slot and screw adjusting means, whereby the correct relative position of escapement levers 62 and 63 with respect to ratchet 52 may be determined. The spacing operation occurs immediately following or subsequent to the printing of a character in the following manner.

Upon the printing of a character, the printing bail 43 oscillates and in so doing controls the operation of lever arm 64. During the initial portion of the clockwise movement of arm 64, lever 63 under the action of spring 65 also rotates clockwise to bring the laterally disposed end 72 into the path of tooth 61a. It is noted that, due to the space indicated at 70 between arm 64 and laterally disposed end 71 of lever 62, the latter lever has not been acted upon, and end 66 thereof remains momentarily in engagement with tooth 61. However, upon the further clockwise movement of lever 64, similar movement is imparted, through laterally disposed end 71, to lever 62, thus effecting the disengagement of end 66 from tooth 61 and permitting ratchet 75

52 to rotate slightly in a clockwise direction under the influence of friction clutch members 54 to 57 (Fig. 5) until arrested by the engagement of tooth 61a with laterally disposed end 72 5 of lever 63 which lever, as was noted, was free to rotate in a clockwise direction under the tension of spring 65 into the path of oncoming tooth 61a. Ratchet 52 is thus restrained from rotation by lever 63 until the completion of the printing 10 of a character at which time printing bail 43 and associated lever 64 are caused to rotate in the opposite direction by the action of a printing cam (not shown). Restraint of lever 62 by lever 64 through end 71 is thereby removed, 15 permitting lever 62 to rotate in a counterclockwise direction under the influence of spring 65 into the path of tooth 61b of ratchet 52. During this counterclockwise movement of lever 64, and after the aforementioned release of lever 62, lever 63 20 is caused to rotate in a like direction due to the action of lever 64 on end 67 thereof, thereby disengaging end 72 of lever 63 from tooth 61a and allowing ratchet 52 to continue its rotation until arrested by the engagement of end 66 of lever 62 25 with tooth 61b. It is observed that with the escapement mechanism just described there is a period of overlap wherein ends 66 and 72, due to the space indicated at 70, are effective simultaneously to prevent the escapement of ratchet 30 52, the ends 66 and 72 being otherwise alternately engageable to permit the escapement of ratchet 52.

It is obvious that since worm 53 and ratchet 52 are integrally connected to sleeve 51, said 35 worm 53 will have normally the same intermittent or step-by-step motion as was hereinbefore seen to be imparted to ratchet 52. Worm 53 is meshed with worm gear 28 (Figs. 2 and 3) which is loosely mounted on vertical shaft 29, and is operably connected thereto by means of jaw clutch 41 (Fig. 3). Worm 53 and gear 28 are so related, according to the present embodiment, that one-third revolution of worm 53 will rotate gear 28 through a distance which, through gear 31 and rack 32, causes the type carriage to be 40 stepped forward one character space.

From the foregoing it will be observed that character spacing occurs automatically with the printing of each character; that is, the spacing function is merged into the printing operation. 50 It is well known that there is a code combination allotted to each type bar, but it is possible, however, to employ a code combination, commonly known as the spacing signal, which is identified 55 with no type bar but which will nevertheless initiate the printing operation. Therefore, the spacing between words is accomplished in exactly the same manner as set forth when a spacing signal is received, except that no type 60 bar is operated and consequently no character is printed.

In accordance with the present invention, 65 multiple spacing may be effected automatically under predetermined operating conditions. The 65 mechanically operated tabulating arrangement of the present embodiment comprises a tabulator bar 81 extending across the front of the printing apparatus, as shown in Fig. 1, which is provided with depending portions 82 and 83 through 70 which bar 81 is pivotally mounted on bracket 84 carried in the printer frame. Thus tabulator bar 81 is adapted to be swingable toward or away from the type carriage 15. Bar 81 is also provided with a longitudinal slot 85 extending substantially the entire length of the bar. In this

slot are carried adjustably movable members 86 which are adapted to be clamped to the bar 81 by means of screws 87 and clamps 88 individual to each member 86 (Fig. 3). As indicated in Fig. 2, these members 86 are each provided with an inclined or cam portion 89, conformed to provide quick action upon cooperation with a cam element 111 carried by the type carriage, to effect the multiple spacing operation. In the embodiment shown, the bar 81 is biased normally toward the element 111 (and hence the type carriage 15) by a spring 110 (Fig. 2) so that members 86 are normally presented in the path of element 111, whereby at predetermined points, governed by the arrangement of members 86, 15 element 111 will cam a member 86 rightwardly, as viewed in Fig. 3, to impart clockwise movement to bar 81 about pivots 80 and 90.

Tabulator bar 81 is also provided, intermediate the depending portions 82 and 83 (Fig. 1) and 20 suitably positioned relative to the spacing mechanism, with another depending portion 91. Attached to and depending from portion 91 is a bar 92 the lower end of which is provided with an inclined cam portion 93 which cooperates with a 25 stud 94 carried at the end of arm 96 of a lever 97 pivoted at 98 to a support 99 secured to the function lever comb 47. Bar 92 is also provided with a retaining portion 95 spaced from portion 93. At the end of arm 102 of lever 97 is pivotally 30 carried a vertically extending member 103, the upper end of which is provided with a pair of arms 104 and 105. The arm 105 is adapted to cooperate with a stud 106 carried by escapement lever 62.

Whenever element 111 coacts with a member 86 to rotate the tabulator bar 81 in a clockwise direction (as viewed in Fig. 3) the cam portion 93 will cause lever 97 to be rotated clockwise against the pull of spring 107 distended between arm 96 and the printer frame. This movement of lever 97 will, through members 103, arm 105, and stud 106, effect the disengagement of end 66 from ratchet 52. The duration of disengagement of end 66 from ratchet 52 is governed by the contour 40 of cam portion 93 on member 86 which is so conformed as to delay the counterclockwise rotation of lever 97 sufficiently to effect the desired amount of rotation of ratchet 52. For example, if the cam portion 93 is so conformed as to permit ratchet 52 to make approximately one complete rotation, the carriage 15 will be stepped or spaced a distance which is in excess of the normal spacing distance, or a number of spaces equivalent to one less than the number of teeth 50 on the spacing ratchet, in the time interval allotted to the reception of a single code combination. For practical reasons the maximum spacing obtained per revolution of the spacing ratchet wheel is not equivalent to the total number of 55 teeth thereon, because it is necessary to stop spacing while printing is effected in order to allot sufficient time to procure a smoothly operating printing operation. Theoretically, it is possible to permit a complete rotation of the spacing 60 ratchet wheel, but in that event the time allotted for printing is shortened so as to require a very sudden printing blow, thus necessitating a slower speed of operation. On the other hand, if the ratchet 52 is only permitted to rotate less than a 65 complete revolution, the spacing movement of carriage 15 will likewise be correspondingly less, or equivalent (in number of spaces) to the number of teeth which are permitted to escape laterally disposed portion 66. Furthermore, since 70 75

the carriage 15 moves, upon a single revolution of ratchet 52, a number of spaces equal to the number of teeth on ratchet 52, it is obvious that if a spacing ratchet 52 is employed having a greater number of teeth thereon (than which is indicated in the drawings), the carriage 15 will be moved a correspondingly greater number of spaces per revolution of the spacing ratchet. However, according to the specific disclosure, the cam portion 89 is so conformed as to cause the spacing operation to be prolonged sufficiently to add one extra space to the normal spacing operation, so that at intervals determined by the spacing of members 86, an additional space is added 15 automatically between adjacent characters.

From the foregoing, it is observed that the carriage 15 is spaced normally a single step upon each cyclic or oscillatory movement of printing bail 43. The same effect would be achieved at those instants when cam element 111 coacts with members 86 were it not for the cam portion 93, the function of which is to cooperate with cam portion 89 to prolong the action of the spacing mechanism to produce multiple spacing. 25 Thus when the coaction between element 111 and a member 86 coincides with the effectuation of a recording operation, the tabulator bar 81 will be rotated clockwise, and cam 93 will cause like rotation to lever 97 substantially simultaneously 30 to the oscillation of printing bail 43 to effect, through vertical member 103, the disengagement of end 66 of pawl 62 from tooth 61. However, printing bail 43 returns immediately to its counterclockwise position tending to return pawl 62, 35 and hence end 66, into engagement with the succeeding tooth on ratchet 52, and if it were not for cam 93, lever 97 would be returned to its counterclockwise position prematurely to permit pawl 62 to respond to the movement of printing bail 43, 40 and consequently multiple spacing would not be achieved. Therefore, due to the cam portion 93, escapement pawl 62 remains disengaged from ratchet 52 until element 111 passes member 86, at which time tabulator bar 81 responds to the 45 pull of its spring 110 and returns to its counterclockwise position, viewed in Fig. 3, thus removing cam 93 from stud 94, whereupon lever 97 is free to respond to the pull of its spring 107 to return to its counterclockwise position shown in 50 Fig. 3. Escapement pawl 62 is thus restored to its effective position after having permitted the carriage 15 to be moved the predetermined number of character spaces.

Cam member 111 is pivoted at 112 (Fig. 2) on a portion 113 integrally formed on a bar 115 which is comparable to bar 53 shown in Fig. 1 of Patent No. 1,904,164 employed for retaining the bell crank levers 13 in operable relation to vanes 107. Cam 111 normally tends to rotate in a clockwise direction (as viewed in Fig. 2) about pivot 112 due to the action of spring 116, but its clockwise rotation is limited by the coaction of a stop pin 117, carried thereon, with the end of bar 115. Thus upon the rightward movement of type 65 carriage 15, cam 111, due to its non-rotatability further in a clockwise direction, will, by its camming action on member 86, actuate tabulator bar 81 outwardly; but upon the leftward movement of type carriage 15, cam 111 upon striking the 70 series of members 86 will be rotated counterclockwise against the action of spring 116 sufficiently to escape the cam portion 89.

In the event that it is desired to use the printer disclosed in the drawings, in the normal manner, 75 that is, without the automatic multiple spacing

feature according to the present invention, a cut-out means is provided for disabling the vertical arm 103 carried on lever 97. The cut-out means, Figs. 2 and 3, comprises a link 121 pivotally connected at 122 to member 103 and at 123 to armature 124 of an electromagnet 125 mounted on a bracket 126 carried in the printer frame. When the magnet 125 is deenergized, the armature 124, link 121, and member 103 will respond collectively to the pull of spring 127 (Fig. 3) to bring arm 105 out of registry with stud 106, the arm 104 acting as a limiting stop to the actuation of member 103 by spring 127. In this manner, further actuation of bar 81 by element 111 will be ineffectual to disengage pawl 62. The magnet 15 125 may be included in a local circuit controlled by a manually operable switch, so that when the circuit is closed the magnet 125 will be energized and member 103 will be actuated to present arm 105 into cooperative relation with stud 106. 20

It is, of course, understood that it is intended to cover not only the specific embodiment disclosed, but also such changes or modifications as come within the spirit of the invention or scope of the following claims. 25

What is claimed is:

1. In a recorder, printing instrumentalities, means movable to form character spaces, and cam actuated means for inserting automatically at predetermined points and independently of the printing instrumentalities an additional character space, said last recited means including further cam means to actuate said first recited means. 30

2. In a recorder, a spacing mechanism, means movable normally one character space in response to the action of said spacing mechanism, means responsive to each recording operation for operating said spacing mechanism, cam actuated means for altering the action of said spacing mechanism, and cam initiated means operable through said cam actuated means for automatically prolonging the action of said spacing mechanism independently of said second recited means a predetermined amount. 40 45

3. In a recorder, printing and spacing instrumentalities, means responsive to the printing instrumentality for controlling the spacing instrumentality, said spacing instrumentality including a pawl and a ratchet wheel, adjustable means, and means operated directly by said adjustable means for a period predetermined by its characteristics for moving said pawl free of said ratchet wheel to alter the effectiveness of said spacing instrumentality. 50 55

4. In a recorder, printing and spacing instrumentalities, means responsive to the printing instrumentality for controlling the spacing instrumentality, said spacing instrumentality including a pawl and a ratchet wheel, adjustable means, and means operated directly by said adjustable means for a period predetermined by its characteristics for moving said pawl free of said ratchet wheel to alter the effectiveness of said spacing instrumentality independently of said printing instrumentality. 60 65

5. In a recorder, spacing means including escapement pawls and a ratchet wheel, means movable normally under control of said spacing means to form character spaces, means for controlling extended operation of said means operated at certain character spaces, and means operated directly by said third recited means to move one of said pawls free of said ratchet wheel 70 75

to cause said spacing means to operate immediately.

6. In a recorder, means to effect recording operations, means to actuate said means to effect 5 character spacing, pawl and ratchet means to limit the movement of said recording means through said mechanism to a single character space at a time, a cam having a particular contour, and means directly responsive to the operation of said cam for moving said pawl free 10 of said ratchet for effecting spacing to an extent dependent on the contour of said cam.

7. In a recorder, means movable to form character spaces, power driven means for causing 15 such movement, a pawl and ratchet escapement mechanism controlling said power driven means, an element operated at certain character spaces, and mechanism actuated directly by said element for moving said pawl free of said ratchet to effect 20 additional character spacing.

8. In a recorder, means movable to form character spaces, power driven means for causing such movement, an escapement mechanism including a pawl and ratchet wheel, an element operated at certain character spaces, and mechanism actuated through said element for moving said pawl free of said ratchet wheel to allow 25 operation of said movable means.

9. In a recorder, means movable to form character spaces, power driven means for causing such movement, an escapement mechanism including a pair of pawls normally drawn toward each other and a ratchet wheel, an element operated at certain character spaces, and mechanism actuated through said element for moving one of said pawls free of said ratchet wheel to allow 30 operation of said movable means.

10. In a recorder, means movable to form character spaces, power driven means for causing such movement, a ratchet escapement mechanism including a pair of pawls normally drawn toward each other, an element operated at certain character spaces, and mechanism actuated through said element for disabling one of said 35 pawls to allow an additional period of operation of said movable means.

11. In a recorder, means to effect recording operations, spacing means therefor, means responsive to said recording means for operating said spacing means, said spacing means comprising a pair of pawls and a ratchet member to limit the movement of said recording means to a single character space at a time, and cam initiated means effective at predetermined points for causing said spacing means to insert an additional character space, said cam initiated means including a further cam means to move one of said pawls free of said ratchet member to effectuate directly the disablement of said spacing means to enable the insertion of said additional character space. 5 10 15

12. In a recorder, means to effect recording operations, spacing means therefor, means responsive to said recording means for operating said spacing means, said spacing means comprising a pair of pawls and a ratchet wheel to limit the movement of said recording means to a single character space at a time, cam actuated means, and means effective directly through the actuation of said cam means for moving one of said pawls free of said ratchet wheel to render said spacing means ineffectual to limit the movement of said recording means to a single character space at a time. 20 25

13. In a recorder, means to effect recording operations, spacing means therefor comprising escapement pawls and a ratchet wheel, means responsive to said recording means for operating said spacing means, said spacing means being adapted to limit the movement of said recording 30 means to a single character space at a time, cam means operable to move one of said escapement pawls free of said ratchet wheel, and an automatic means effective independently of said recording means to operate said cam means to render said spacing means ineffectual to limit the movement of said recording means for a predetermined period. 35 40 45

ALBERT H. REIBER. 45
